UNITED STATES PATENT OFFICE.

CALEB M. LARSON, OF MINNEAPOLIS, MINNESOTA.

SAW-SET.

961,503.

Specification of Letters Patent. Patented June 14, 1910.

Application filed April 22, 1909. Serial No. 491,423.

To all whom it may concern:

Be it known that I, CALEB M. LARSON, a citizen of the United States, residing at Minneapolis, in the county of Hennepin and

5 State of Minnesota, have invented certain new and useful Improvements in Saw-Sets; and I do hereby declare the following to be a full, clear, and exact description of the invention, such as will enable others skilled in 10 the art to which it appertains to make and use the same.

My invention has for its object to provide a simple and highly efficient saw-set, and to this end it consists of the novel devices and 15 combinations of devices hereinafter described and defined in the claims.

In the accompanying drawings which illustrate the invention, like characters indicate like parts throughout the several 20 views.

Referring to the drawings: Figure 1 shows an improved saw-set in front elevation; Fig. 2 is a view chiefly in section on the line $x^2 x^2$ of Fig. 1, with some parts 25 shown in full; Fig. 3 is an end elevation of the saw-set; and Fig. 4 is a detail view in plan, showing the so-called anvil block removed from working position.

The body 1 of the tool is preferably a 30 malleable iron or steel casting, provided at one end with a pair of curved arms 2 that are located on the same side of the longitudinal axis of the frame, and terminate at 35 their outer ends in a flat approximately disk-like head 3, the axis of which is alined with the longitudinal axis of said frame, leaving a lateral opening 4 at the front side of the tool. At its other end, the frame 1 is provided with laterally spaced flanges 40 5, to which a pair of levers 6 and 7 are pivotally connected. At their pivotal ends, the levers 6 and 7 are shown as provided with rounded plunger engaging lugs 8, and stop lugs 9, which latter engage the frame 1 and 45 limit the outward movements of the said levers. Mounted in the frame 1 for endwise movements longitudinally thereof, is a pair of plungers 10 and 11, the rear ends of 50 which engage with the lugs 8 respectively of the levers 6 and 7.

The intermediate portion of the frame 1 is cut away as shown at 1^a. On the plungers 10 and 11, within the opening 1^a, are coiled springs 12 and 13, respectively, which 55 press against the outer extremity of the opening 1^a and against the pins 14, shown

as driven through the said plungers 10 and 11. These springs 12 and 13 therefore, normally hold the levers 6 and 7 with their stop lugs 9, bearing against the frame 1. 60 The plunger 10 serves as the saw setting plunger, and the inner end thereof is preferably beveled. To the inner end of the plunger 11 a disk-like saw clamping head 15 is secured. For coöperation with the setting plunger 10, and the clamping head 15, a so-called anvil block is provided, and this anvil block is preferably in the form of a heavy disk 16, which is adjustably secured on the inner face of the head 3. The inner 70 face of the anvil block 16 is provided with a marginal bevel 16^a, the bevel of which varies circumferentially from minimum to maximum, so that by rotation of said block, the portion having the desired degree of 75 bevel may be turned into line with the setting plunger 10. The said anvil block is adjustably secured to the head 3 by a bolt 17, the head of which is shown as countersunk into said block, and the end of which 80 is provided with a thumb nut 18 that clamps the outer face of said head 3. The intermediate portion of the bolt 17 is passed through a rectangular guide block 19, that is mounted for sliding movements in a slot 85 20 formed in the central portion of the head 3. The said anvil block 16 is thus mounted for rotary adjustments, and for sliding movements, the latter adjustment serving to project the beveled edge of the said anvil 90 block more or less beyond the beveled end of the setting plunger 10, depending on the length of the saw tooth that is to be set. The amount of set that will be given to the 95 saw tooth may be varied by rotary movement to the said anvil block.

The guide block 19 is set and held in different positions by a small screw 21 which is swiveled in the head 3, and is provided with a knurled head 22, by means of which 100 it may be rotated to adjust said block 19 when the clamping nut is loosened. Preferably the anvil block 16 is marked or graduated on its periphery to indicate the different extents of its bevel 16^a at different 105 circumferential points.

The spring 12 which retracts the setting plunger 16 should be considerably stronger than the spring 13 which retracts the clamping plunger 11, and its head 15. 110 When the springs are thus relatively strong, and the two levers are gripped in the hand

and forced toward each other, the spring 13 will first yield and permit the clamping head 15 to press the saw Y against the anvil block 16, and then the spring 12 will yield 5 and the setting plunger 10 will be forced against the tooth of the saw, thereby setting the same. It will thus be seen, that the saw is clamped and firmly held before the setting plunger is forced against the tooth, 10 and this insures accuracy in the upsetting action.

The improved saw-set, while of comparatively simple construction, is highly efficient for the purposes had in view, and is capable 15 of such adjustments as are required to adapt the device for the setting of teeth of various kinds of saws.

What I claim is:

1. In a saw-set, the combination with a 20 frame, of a lever actuated spring retracted setting plunger mounted in said frame, a guide block mounted in a projecting portion of said frame for sliding movement, an anvil block mounted for sliding adjustment 25 on the projecting portion of said frame and rotatively secured to said guide block and said anvil block provided on its working face with a varying bevel for coöperation

with said setting plunger, substantially as described.

2. In a saw-set, the combination with a 30 frame, of a clamping plunger and a setting plunger mounted in said frame, levers for actuating said plungers, a relatively strong spring retracting said setting plunger and a relatively weak spring retracting said 35 clamping plunger, a guide block slidably mounted in a recess in a projecting head portion of said frame, a screw swiveled in said head portion and having threaded engagement with said guide block for positively moving the same, an anvil block having its working face formed with a varying bevel for coöperation with said setting plunger, and said anvil block being rotatively 40 secured to said guide block and arranged for sliding movement therewith, and means for clamping said anvil block to said head portion, substantially as described.

In testimony whereof I affix my signature 50 in presence of two witnesses.

CALEB M. LARSON.
